DESIGN FOR A WATCH

George Waller Blow, New York, N. Y., assignor to
General Time Instruments Corporation, New
York, N. Y., a corporation of Delaware

Application May 1, 1940, Serial No. 92,059

Term of patent 7 years

To all whom it may concern:

Be it known that I, George Waller Blow, a citizen of the United States, residing in the city of New York, in the county of New York and State of New York, have invented a new, original, and ornamental Design for a Watch, of which the following is a specification, reference being had to the accompanying drawing, forming a part thereof.

Figure 1 is a front elevational view of the watch showing my new design;

Figure 2 is a side view thereof;
Figure 3 is a back view thereof; and
Figure 4 is a side view of the watch when used as an easel watch on a desk or other flat surface.

I claim:

The ornamental design for a watch, as shown and described.

GEORGE WALLER BLOW.
